(57) **CLAIM**

The ornamental design for a medical biochemical analyzer, as shown and described.

DESCRIPTION

FIG. 1 is a top, front and right side perspective view of a medical biochemical analyzer showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a top, front and right side perspective view thereof, in a state where the lid is opened;

FIG. 8 is a front elevational view thereof, in the state where the lid is opened;

FIG. 9 is a left side elevational view thereof, in the state where the lid is opened; and,

FIG. 10 is a cross-sectional view thereof taken along lines X-X of FIG. 2, in which an internal structure thereof is shown.

The broken lines shown in FIG. 10 illustrate portions of the medical biochemical analyzer that form no part of the claimed design. The broken lines that lie directly adjacent to the perimeter of the claimed area illustrate a boundary that forms no part of the claimed design.
